UNITED STATES PATENT OFFICE.

WARREN MCARTHUR, OF CHICAGO, ILLINOIS, ASSIGNOR TO THE R. E. DIETZ COMPANY, OF NEW YORK, N. Y., AND THE STEAM GAGE AND LANTERN COMPANY, OF SYRACUSE, NEW YORK.

TUBULAR LAMP.

SPECIFICATION forming part of Letters Patent No. 465,597, dated December 22, 1891.

Application filed March 5, 1891. Serial No. 383,827. (No model.)

To all whom it may concern:

Be it known that I, WARREN MCARTHUR, a citizen of the United States, residing at Chicago, in the county of Cook and State of Illinois, have invented a new and useful Improvement in Tubular Lamps, of which the following is a specification.

This invention relates to the oil-fount and connecting parts of that class of tubular lamps in which the oil-fount is surrounded by an air jacket or casing which receives the air from the tubes at the bottom and through which the air ascends around the oil-fount to the burner mounted on the same. A lamp of this construction is shown, for instance, in the patent to L. F. Betts, No. 218,917, August 26, 1879.

The object of my invention is to provide the lamp with a glass fount in such manner that the contents can be seen through the surrounding air-jacket, thereby rendering it unnecessary to remove the fount from the jacket in order to ascertain the height of the oil-level.

In the accompanying drawings, Figure 1 is fragmentary elevation of the lower portion of a tubular lamp provided with my improvements. Fig. 2 is a vertical section in line *xx*, Fig. 1. Fig. 3 is an elevation of the oil-fount and surmounting parts removed from the air-jacket. Fig. 4 is a horizontal section in line *yy*, Fig. 2. Fig. 5 is a fragmentary perspective view, and Fig. 6 a fragmentary horizontal section illustrating a modified construction of my improvement.

Like letters of reference refer to like parts in the several figures.

A represents the lower portions of the air-tubes; B, the collar into which they open and which has an open upper end; C, the post-socket secured in said collar, and D the supporting-post.

E represents the air-jacket, which has its bottom provided with a central opening having an upturned flange *e*, by which the air-jacket rests on the upper end of the collar B.

F is the glass oil-fount, which is arranged

within the air-jacket in such manner that the air entering through the central opening in the bottom flows outwardly underneath the bottom of the oil-fount and upwardly along the sides of the same. As shown in the drawings, the oil-fount is attached to a top plate H by rods *h*, and suspended in the air-jacket by the top plate resting with its marginal portion upon an annular bead *i*, formed in the upper portion of the air-jacket. It is obvious, however, that the oil-fount can be supported upon ribs or projections secured to the bottom of the air-jacket.

The oil-fount is provided in its top with a screw-threaded collar *j*, to which a metallic burner-seat J is secured. K represents the burner seated in this seat, and L represents the burner-cone, resting with its skirt upon the top plate H, which is provided with a central opening somewhat larger in diameter than the burner, so that the air ascending along the sides of the oil-fount passes inwardly between the top of the fount and the top plate, and so reaches the burner.

M represents openings formed in the side wall of the air-jacket, preferably diametrically opposite each other, so that the contents of the transparent oil-fount can be viewed through these openings. The oil-fount is provided on its sides with lateral enlargements N, which fit against these openings and whereby the transparent walls of the fount are brought out nearly flush with the air-jacket, which arrangement greatly facilitates the observation of the oil in the fount. These enlargements serve, further, to close the air-space O, which exists between the side of the fount and the jacket and prevent the ingress or egress of air to and from this air-space through the side openings. The openings in the jacket are preferably provided with inwardly-projecting flanges *p*, which

make a close joint with the lateral enlargements of the fount. If desired, the lateral enlargements may be omitted and the flanges *p* be extended inwardly to fit against the side of a cylindrical fount, as represented in Figs.

5 and 6. In this construction the fount is preferably provided with upright ribs q , which fit against the upright flanges and assist in making a close joint between the fount 5 and the air-jacket at the openings.

R represents the vertically-adjustable tray upon which the wick rests, and whereby the time during which the lamp burns is regulated. This tray is also exposed to view through 10 the side openings.

I claim as my invention—

1. The combination, with the air-jacket provided with a side opening, of a transparent oil-fount arranged within the air-jacket and 15 separated therefrom by an air-space and having a lateral enlargement which fits against

the opening in the jacket, substantially as set forth.

2. The combination, with the air-jacket provided with a side opening surrounded by inwardly-projecting flanges, of a transparent oil-fount arranged within the air-jacket and separated therefrom by an air-space, the fount bearing against said flanges, whereby the air-space is closed around the opening, substantially as set forth.

Witness my hand this 26th day of February, 1891.

WARREN MCARTHUR.
